(57) CLAIM

The ornamental design for a pair of women's shoes, as shown and described.

DESCRIPTION

FIG. 1 is a front perspective view of a pair of women's shoes, showing my new design;

FIG. 2 is a top view thereof;

FIG. 3 is a bottom view thereof;

FIG. 4 is a front view thereof;

FIG. 5 is a rear view thereof;

FIG. 6 is a left side view of the left shoe;

FIG. 7 is a right side view of the left shoe;

FIG. 8 is a right side view of the right shoe; and,

FIG. 9 is a left side view of the right shoe.

Features shown in dashed lines immediately adjacent the shaded areas or adjacent the solid lines represent the bounds of the claim and all other dashed lines are for illustrative purposes only. None of the dashed lines form a part of the claimed design.
